UNITED STATES PATENT OFFICE.

DANIEL TETLOW, OF PHILADELPHIA, PENNSYLVANIA, ASSIGNOR TO HENRY TETLOW & BROTHER, OF SAME PLACE.

DESIGN FOR AN ATOMIZER.

SPECIFICATION forming part of Design No. 14,598, dated January 19, 1884.

Application filed November 4, 1883. Term of patent 14 years.

To all whom it may concern:

Be it known that I, DANIEL TETLOW, a citizen of the United States, residing in the city and county of Philadelphia, State of Pennsylvania, have invented and produced a new and original Design for an Atomizer, of which the following is a specification, reference being had to the accompanying drawings, forming part thereof.

Figure 1 is a side elevation of an atomizer embodying my design. Fig. 2 is a front view thereof.

Similar letters of reference indicate corresponding parts in the two figures.

The leading feature of my design is the body and bulb simulating the form of a pistol or fire-arm, as will be hereinafter fully set forth.

In the drawings, A represents the body of an atomizer, B the bulb at the rear thereof, and C the neck between the body and bulb.

The body A is of the form of a cylinder, a, a tube, b, of less diameter than the cylinder a,

a stem or stopper, c, a bent or angular-shaped piece, d d', a depending piece, e, and segmental piece f. The chamber a is of the form of 25 the cylinder of a pistol, the tube b that of the barrel thereof, the stopper c that of the rammer thereof, the piece d d' that of the hammer thereof, and the piece e that of the trigger thereof, the segmental piece f simulating 30 a trigger-guard. The bulb B extends diagonally downward from the rear of the chamber, and, while constituting the handle of the atomizer, simulates the handle or grip of a pistol, the design thus being unique and attractive.

I claim—

A design for an atomizer, consisting of a cylinder, a, tube b, stem c, piece d d', depending piece e, and piece f, as shown and described. 40

DANIEL TETLOW.
